CLAIM

We claim the ornamental design for a media processing device, as shown and described.

DESCRIPTION

FIG. 1 is a first perspective view of a first embodiment of a media processing device, showing our new design;

FIG. 2 is a second perspective view thereof;

FIG. 3 is a front view thereof;

FIG. 4 is a rear view thereof;

FIG. 5 is a top view thereof;

FIG. 6 is a bottom view thereof;

FIG. 7 is a first side view thereof; and

FIG. 8 is a second side thereof.

FIG. 9 is a first perspective view of a second embodiment of a media processing device;

FIG. 10 is a second perspective view thereof;

FIG. 11 is a front view thereof;

FIG. 12 is a rear view thereof;

FIG. 13 is a top view thereof;

FIG. 14 is a bottom view thereof;

FIG. 15 is a first side view thereof; and,

FIG. 16 is a second side thereof.

Broken lines are directed to environment and are for illustrative purposes only.
